ROCK DRILL FEEDING MECHANISM

Gustav C. Pearson and Ivan S. Carpenter, Denver, Colo., assignors to Gardner-Denver Company, Denver, Colo., a corporation of Delaware

Application March 12, 1934, Serial No. 715,149

28 Claims. (Cl. 121—9)

The invention relates to improvements in rock drills and is more particularly directed to means for automatically feeding such drills to and from their work.

5 The object of the present invention is to provide a novel and effective means, independent of any action of the drilling unit, for feeding a drilling unit to and from its work.

Another object of the invention is to provide 10 fluid actuated means under the full control of the operator for moving a drilling unit longitudinally of its support.

Still another object of the invention is to provide fluid operated means for moving a rock drill 15 upon its support, said means being adapted to move the drill in any longitudinal direction, to lock the drill against movement, and to free the drill so that it might be moved by hand upon its support.

20 Another object of the invention is to provide automatic feeding means for a drill operable at such periods as to assure the correct striking relation between the drill hammer and the steel.

Further objects of the invention will be apparent 25 from the description made hereinafter, and to all of these ends the invention consists of the features of construction, arrangement of parts, and combination of elements substantially as described in the specification, claimed and shown 30 in the accompanying drawings in which:

Figure 1 is a side elevation of a rock drill mounted upon a support and having connected thereto one example of the feeding device constituting the present invention.

35 Figure 2 is a top plan view of the support showing positioned therein reversely arranged racks and the means for permitting longitudinal movement of the racks with respect to the support.

Figure 3 is an enlarged vertical sectional view 40 showing a portion of a drill with the feeding device connected thereto.

Figure 4 is a diagrammatic view illustrating one form of an automatic valve for controlling the movement of the piston in the feeding device.

45 Figure 5 is a sectional view on the line 5—5 of Figure 3, through the cylinder, piston and valve of the feeding device.

Figure 6 is a vertical sectional view through a portion of the feeding device showing the hand controlled lever for moving the various pawls into and out of engagement with their respective racks.

Figure 7 is a plan view on the line 7—7 of Figure 6 showing the staggered arrangement of the various rack engaging pawls.

55 Figure 8 is a perspective view illustrating in detail the stationary pawls carried by the cylinder of the feeding device and shows both pawls engaging their respective racks, locking the device against movement.

Figure 9 is a similar view showing in detail the pawls carried by the piston with one pawl engaging its rack, while the other pawl is elevated.

Figure 10 is a sectional view on the line 10—10 of Figure 3 showing the stationary pawls lowered as in Figure 8.

Figure 11 is a sectional view on the line 11—11 of Figure 3 showing the pawls carried by the piston in a lowered position.

Figure 12 is a sectional view on the line 12—12 of Figure 2 and illustrates the manner of mounting the rack plate within the support, and

Figure 13 is a perspective view showing a portion of the rack plate.

Briefly, the present invention contemplates the provision of a fluid operated feeding device adapted to be associated with a rock drill to move the same to and from its work. It will, of course, be understood that in the operation of the rock drill as the steel advances into the rock it is the purpose of the feeding device to automatically feed the drill forward, maintaining it in such a position with respect to the work as to obtain the proper striking relation of the drill hammer with the steel. In the accompanying drawings the device is shown as a part of the drill, this is merely one modification. However, such a structure tends to simplify the unit as it combines the two main control valves in one. If desired, the feeding device may be wholly independent of the drill and connected thereto in any suitable manner, or it may merely slide in the support and abut the drill feeding it forward.

In the present embodiment, the feeding device includes a cylinder having therein a reciprocating piston, controlled in its movements by an automatic valve of any desired structure. The device is slideable in the guideways of a support, in rear of the drill, and is provided with two sets of selectively controlled pawls, one set being mounted in an end wall of the feed cylinder, while the other set is mounted in a head carried by the piston, both sets being engageable with racks in the bottom of the support. It is through the medium of these pawls and racks that movement of the drill, and device, longitudinally of the support is accomplished.

The pawls are controlled at the will of the operator and may be moved with respect to their racks so as to lock the device against either forward or rearward movement, or against movement in both directions. Furthermore, the pawls may be so controlled as to free the drill and device of any functioning connection with the support, permitting manual movement of the drill and device in either direction upon the support.

Referring to the drawings in detail, the numeral 60

5 indicates a conventional mounting shell having a cone 6 by which the shell may be suitably secured to a mounting. The shell 5 includes a bottom 7 and upstanding side walls 8, the inner faces of the latter being provided with longitudinally extending grooves constituting guideways 9 in which the rock drill and its feeding device, hereinafter described, are positioned for longitudinal movement.

10 The upstanding walls of the shell 5 are further provided, on their inner faces adjacent the bottom 7, with longitudinal grooves 10 receiving therein projections 11 formed upon the side edges of a removable plate 12. The upper face of this

15 plate 12 carries reversely arranged racks 13 and 14.

To maintain the rack plate 12 in place within the shell and yet provide a slight longitudinal movement of the plate, the ends of the guide shell are closed by cross arms 15 maintained to the shell by bolts 16 passing through outstanding ears 17. The bolts 16 extend beyond the ears 17 and have positioned thereabout, between the ears 17 and the usual lock nuts 18, coil springs 19. With this structure it will be apparent that the rack 12, even though its ends abut the cross arms 15, has a slight longitudinal movement, due to the yielding action of the cross arms, with respect to the guide shell, and this movement reduces the shock and strain upon the racks during the engagement of the various operating pawls therewith.

In Figures 1 and 3 a rock drill 20 is shown of any desired construction and which may be mounted for movement in the shell 5. In the present embodiment the drill includes a cylinder 21 having the usual outstanding flanges, not shown, which slidably engage the guideways 9 of the shell 5. The cylinder has therein a reciprocating piston hammer 22 intended to impart blows to a drill steel 23 supported in the front end of the drill. The movement of the hammer being controlled by a suitable automatic valve, the chest of which is shown at 24. In rear of the chest 24 the cylinder 21 has positioned therein suitable means, indicated at 25, for imparting rotary movement to the hammer and ultimately the steel. To move the drill 20 longitudinally of the shell 5 there is arranged, in rear of the cylinder 21, a complete fluid operated motor generally indicated at 26.

Referring more particularly to Figure 3 the feeding motor includes a cylindrical chamber 27 having therein a reciprocating piston 28 controlled in its movement by an automatic valve 29 of any desired type. The chamber 27 is formed in an intermediate plate 30 and end sections 31 and 32. The end section 32 is provided with outstanding flanges 33, Figure 10, for engagement in the guideways 9 of the shell 5, to maintain the feeding device in alignment with the rock drill.

It will be observed that the piston 28 is provided with front and rear extensions 34 and 35, the former reciprocating within a bore provided in the end plate 31 for the purpose of preventing any misalignment of the piston within the cylinder when lateral strain is applied to the extension 35 in a manner hereinafter set forth.

In rear of the end plate 32 there is positioned a back head 36 spaced from the plate 32 by an integral hood structure 37, serving to enclose the free end of the piston extension 35. The back head 36 has mounted therein the usual fluid control valve 38, the water tube 39 which conveys water from a suitable rear connection to the steel

and a manually operated lever for moving the rack engaging pawls.

The various sections forming the feeding device are connected to the rock drill and made a part thereof by suitable side rods 40.

Referring now to Figures 3, 6, 8, and 9 it will be observed that two sets of rack engaging pawls are provided, one set, referred to hereinafter as the stationary pawl, being mounted for vertical movement within the end plate 32, more clearly shown in Figure 10. All pawls being provided with enlarged feet having teeth engageable with their respective racks and held in such engagement by suitable springs.

As shown in the above figures, the pawls constituting the stationary set are indicated at 41 and 42. These pawls are spaced apart and their adjacent sides are provided with undercut portions forming lips 43, adapted to be engaged by outstanding flanges 44 formed longitudinally upon a control shaft 45, positioned between the pawls and mounted for oscillatory movement in the back head 36 and a socket 46 formed in the end plate 32. The shaft 45 is provided with an operating handle 47.

To hold the shaft 45 in any desired position, to elevate or lower the pawls, there is positioned about the shaft a removable tapered bearing 48 held against rotary movement, with respect to the back head, by a projection 49 fitting within a slot 50 formed in the back head. The front edge of the bearing 48 carries V shaped notches 51, 52 and 53, any one of which being adapted to receive therein an outstanding pin 54 fixed in the shaft 45. To maintain engagement of the pin 54 within any desired notch, the free end of the shaft 45 is provided with a bore having positioned therein a spring pressed plunger 55, the end of which abuts the end wall of the shaft socket 46 formed in the end plate 32.

The rear extension 35 of the piston has detachably connected thereto a depending head plate 56 having a bore 57 through which the shaft 45 passes. Upon lateral sides of the bore 57 there are provided vertical sockets having therein spring pressed pawls 58 and 59. These pawls being of a structure similar to those previously described and provided with lips 60 adapted to be engaged by the outstanding flanges 44 of the shaft 45. The head plate 56 and the piston extension 35 being covered at all times, and during their movement, by the hooded portion 37 of the back head 36.

Referring to the means for controlling the movement of the various pawls it will be observed that Figures 1 and 3 disclose the pawls for feeding the drill and device forward as engaging the rack 14. To secure this functioning position of the pawls, the operating handle 47 is swung to the left to permit the pin 54, carried by the shaft, to engage the notch 53. Such oscillation of the shaft lowers the stationary pawl 42 and the pawl 58 carried by the piston, while the stationary pawl 41 and the piston carried pawl 59 are raised out of engagement with the rack 13. Such position of the pawls, upon operation of the piston, moves the drill and feeding device forward of the guide shell step by step.

After the drill has moved forwardly the desired distance, the operating handle 47 is then moved to the extreme right position whereupon the shaft pin 54 will engage the V notch 51. Such movement of the shaft 45 lowers the stationary pawl 41 and the piston carried pawl 58 to engage the rack 13, at the same time raising pawls 42

and 59 from their engagement with the rack 14. Movement of the piston with the pawls in these positions tends to move the drill and feeding device rearwardly of the support.

5 It is, of course, understood that in the forward and rearward movements of the feeding device the hammer of the drill continues in operation, and that it will play a very important part in withdrawing the steel from the hole, giving to 10 the steel sufficient jar or vibration to free it should it become stuck.

At some periods of operation it is desirable to lock the feeding device against movement and to accomplish this the operating handle is moved to 15 permit the engagement of the shaft pin 54 with the V notch 52, thus oscillating the shaft 45 to the position shown in Figure 8, whereupon the pawls of both sets will be free to move downward under the influence of the springs to engage their 20 respective racks.

At certain periods in the operation of a drifting drill it is customary for the operator to grasp the drill and move the same longitudinally upon its support; this is merely a time saver, as it 25 eliminates the turning of the usual hand crank. Such movement of a drill equipped with this feeding device is permissible. To accomplish this, assuming that the operator has drilled the hole and wishes to withdraw the drill from the steel 30 without utilizing the feeding device, the operating handle of the shaft 45 is oscillated to permit the pin 54 to engage the V notch 51, whereupon the pawls 42 and 59 which engage the rack 14 are elevated and the pawls 41 and 58 are lowered to engage the rack 13. With the pawls in 35 this position and the throttle valve 31 closed, the operator may then grasp the rear end of the unit and pull the drill backward upon its support. To manually move the unit forwardly, the 40 pawls 42 and 59 are lowered, while the pawls 41 and 58 are elevated.

It is, of course, apparent that in the reciprocation of the piston and the engagement of the pawls with the racks that some shock is imparted 45 to the rack plate. To eliminate or reduce this shock and breakage of the pawl and rack teeth, the rack plate is resiliently mounted as previously described.

The automatic distributing valve indicated at 50 29 is positioned within a bore 61 formed in the intermediate section 30 and closed by the end plates 31 and 32. With the various parts in position as shown in Figure 3 operating fluid passes from the control valve 38 through a passageway 55 62 to an annular groove 63 arranged in the front face of the end plate 31. From this annular groove 63 fluid passes to the automatic valve of the rock drill and through the passageway 64 to the bore 61 in which the valve 29 of the feeding 60 device operates. Entrance to the bore for the motive fluid being supplied through port 65 as shown in the diagrammatic view constituting Figure 4.

It will be observed that Figure 3 illustrates the 65 piston 28 and valve 29 in one of their two functioning positions while Figure 4 shows them in the other position.

With the piston and valve in position as shown in Figure 4 the general operation of the valve is 70 in the following manner, motive fluid passes freely from the port 65 through the valve into the passageway 66 leading to the piston chamber 27 in rear of the piston. The piston will then be driven forwardly, the exhaust to atmosphere from 75 the front piston chamber 17 being through the

passageway 67, bore 61, valve 29 and exhaust port 68. When the piston is in its front position with the automatic valve shifted forwardly motive fluid then passes from the supply port 65 through the passageway 67 and into the piston chamber 27 in front of the piston while that portion of the piston chamber 27 in rear of the piston is open to atmosphere through the passageway 66, bore 61 and exhaust port 69. The piston then moves rearwardly. This cycle of 10 operation then repeats itself.

For the purpose of effecting the shifting movements of the valve there is provided passageways 70 and 71 which connect with intermediate portions of the piston chamber 27 and are covered 15 and uncovered by the piston during its movement. With the valve in position as shown in Figure 4 and motive fluid being supplied through the passageway 66 to the rear face of the piston, the piston moves forward and the passageway 70 is uncovered, permitting fluid to flow to the front face of the valve moving the valve to its second functioning position, that shown in Figure 3, whereupon fluid will then pass from the supply port 65 through the passageway 67 to the 20 front face of the piston. As the piston moves rearward the passageway 71 is uncovered, permitting active fluid to engage the rear face of the valve moving the same to the position shown in Figure 4, whereupon the cycle is repeated. 30

Assuming now that the various parts of the feeding device are in position as shown in Figure 3, whereupon the drill is to move forwardly of the guide shell, motive fluid from the passageway 64 is admitted by the valve 29 to the front 35 piston chamber 27, through the passageway 67, and inasmuch as the pawl 59 carried by the piston is in engagement with the rack 14, movement of the piston rearwardly is prevented. However, the fluid in the chamber 27 will be active upon 40 the end of the cylinder bore moving the drill forward equal to the degree of penetration of the steel, operated upon by the hammer 22 of the drill, into the ore. When the unit has moved sufficiently the passageway 71 is uncovered, permitting motive fluid to pass to the rear end of the automatic valve, moving the same to the position shown in Figure 4. After the valve has 45 shifted to this second position, motive fluid is then admitted into the rear piston chamber 27, 50 whereupon the piston moves forwardly and the pawl 59 carried thereby engaging an advanced portion of the rack 14. During the forward movement of the piston the passageway 70 is uncovered permitting motive fluid to pass from 55 the chamber 27 to the front end face of the valve, shifting the valve to the position first described. This cycle of operation continues until the drill has assumed its desired forward position. 60

During this forward movement of the drill and feeding device the pawl 42 engaging the rack 14 prevents any rearward movement of the drill and device which may be affected by vibration or during the movement of the piston to secure a 65 new engagement with the rack.

Upon the reverse movement of the drill the shaft 45 is oscillated so that the pawls 41 and 58 will engage the rack 13, while the pawls 52 and 59 will be elevated. In this position of the pawls, 70 motive fluid will be active in a manner similar to that described in the forward movement of the unit, with the exception that inasmuch as the pawl 58 carried by the piston prevents the piston from moving forwardly, fluid will be active 75

upon the rear end wall of the piston chamber, moving the unit until the passageway 70 is uncovered, tripping the valve and admitting fluid to the front face of the piston, moving the same rearwardly and permitting the pawl 58 to engage an advanced rear portion of the rack 13. Upon the rearward movement of the piston the passageway 71 is uncovered admitting fluid from the chamber 27 to the rear end face of the valve, tripping the valve to the position shown in Figure 4, whereupon the cycle of operation just described is repeated. The pawl 41 in this operation prevents undue forward movement of the unit.

From the foregoing it is thought that the construction, operation and many advantages of the herein described invention will be apparent to those skilled in the art without further description, and it will be understood that various changes in the size, shape, proportion and minor details of construction may be resorted to without departing from the spirit or sacrificing any of the advantages of the invention.

What we claim is:

1. The combination with a rock drill support 25 having a guideway, of a rock drill slidable therein, a feed motor for the drill including a constantly reciprocating piston, said feed motor being slidable in the guideway and connected to the drill, reversely arranged racks positioned within 30 the support, and selectively controlled pawls carried by the piston and engageable with the racks for moving the drill back and forth upon the support.

2. The combination with a rock drill support, 35 of a rock drill slidable thereon; a fluid operated motor connected to the drill and movable therewith, said motor including a cylinder and a piston, pawls carried by the cylinder and piston and engageable with the support, and said cylinder and 40 piston pawls when moved with respect to each other by fluid alternately engaging portions of the support for moving the drill thereupon.

3. The combination with a rock drill support, of a drill slidable thereon, a feed motor for the drill 45 comprising a cylinder member fixed to the drill and a reciprocating piston member movable in the cylinder, and mechanism carried by the cylinder and piston for alternately engaging portions of the support to move the drill thereupon.

50 4. The combination with a rock drill support, of a drill slidable thereon, a feed motor for the drill comprising a cylinder member fixed to the drill and a reciprocating piston member movable in the cylinder, and selectively controlled mechanisms carried by the cylinder and piston for alternately engaging portions of the support to move the drill in opposite directions thereupon.

55 5. The combination with a rock drill support, of a drill slidable thereon, a feed motor for the drill comprising a cylinder member fixed to the drill and a reciprocating piston therein, a rack on the support, and pawls carried by the cylinder and piston for alternately engaging the rack to move the drill upon the support.

60 6. A drilling unit comprising a pair of longitudinally arranged cylinders; a constantly reciprocating piston in each cylinder, one for striking the drilling steel and the other for imparting motion to the unit; a common valve controlling the flow of fluid to each cylinder; a support for the unit; and means carried by the last named piston and its cylinder for alternately engaging the support to move the unit longitudinally thereupon.

65 7. The combination with a rock drill support, 70 of a drill slidable thereon, a feed motor for the

drill comprising a cylinder member fixed to the drill and a constantly reciprocating piston member movable in the cylinder, reversely arranged racks on the support, selectively controlled pawls carried by the piston and cylinder and engageable with the racks to move the drill in reverse direction thereupon, and said pawls being further controlled to permit manual movement of the drill upon the support. 5

8. The combination with a rock drill support, 10 of a drill slidable thereon, a feed motor for the drill comprising a cylinder member fixed to the drill and a reciprocating piston member movable in the cylinder, reversely arranged racks on the support, selectively controlled pawls carried by the 15 piston and cylinder and engageable with the racks to move the drill in reverse direction thereupon, and said pawls being further controlled to lock the drill against movement with respect to the support. 20

9. The combination with a rock drill support, of a drill slidable thereon, a feed motor for the drill comprising a cylinder member fixed to the drill and having a constantly reciprocating piston therein, reversely arranged racks on the support, movable pawls carried by the piston and cylinder and engageable with the racks to move the drill in reverse directions thereupon, an oscillatory element adjacent the pawls, and said element controlling the engagement of the pawls 30 with the racks. 25

10. The combination with a rock drill support, of a drill slidable thereon, a feed motor for the drill comprising a cylinder member fixed to the drill and having a constantly reciprocating piston therein, reversely arranged racks on the support, vertically movable pawls carried by the piston and cylinder and engageable with the racks to move the drill in reverse directions thereupon, said pawls arranged in pairs and having 40 an oscillatory member therebetween, and said oscillatory member when moved permitting the engagement of one pawl from each pair with its respective rack and the disengagement of the remaining pawls from their respective rack. 45

11. A drilling unit comprising a pair of fluid operated motors each having a piston, one for striking a steel and the other for imparting motion to the unit, a support for the unit, and means carried by the motion imparting piston 50 and motor to alternately engage the support for moving the unit thereupon.

12. A drilling unit comprising a pair of fluid operated motors each having a piston, one for striking a steel and the other for imparting motion to the unit, a support for the unit, elements carried by the motion imparting piston and motor for alternately engaging the support to move the unit thereupon, and means operating said elements to control the directional movement of 60 the unit. 55

13. The combination with a rock drill support, of a rock drill slidable thereon, a feed motor for the drill including a continuously reciprocating piston, said feed motor being slidable 65 upon the support and adjacent the drill, and said piston engaging the support to move the drill step by step longitudinally thereupon.

14. The combination with a rock drill support of a rock drill slidable thereon, a feed motor for the drill including a piston movable at certain intervals with respect to the support, a valve controlling the flow of fluid active upon the piston, said piston having elements engaging the support, means responsive to the move- 75

ment of the piston for actuating said valve, and the intervals during which the piston moves being governed by the movement of the drill upon the support.

5 15. A drilling unit comprising a support having a rock drill slidable thereupon, a feed motor for the drill including a piston, said piston having elements engageable with the support to move the drill thereupon, means controlling the 10 movement of the piston, means responsive to the movement of the drill for actuating the first said means, and said means being controlled by the movement of the drill upon the support.

15 16. The combination with a rock drill support of a rock drill slidable thereon, a feed motor for the drill having a reciprocatory piston member therein, and selectively controlled mechanisms carried by the motor and piston for alternately engaging portions of the support to move the 20 drill thereupon.

25 17. Rock drill advancing means comprising in combination a fluid operated device having piston and cylinder elements, one of which elements is securable to the drill, means to admit driving fluid alternately to opposite sides of the piston substantially at the ends of the piston and cylinder strokes, and means separately to hold the said two elements against movement in one direction to enable them to perform alternate step by step advancing movements in the 30 opposite direction when the said device is operative.

35 18. Rock drill advancing means comprising in combination a fluid operated device having piston and cylinder elements, one of which elements is securable to the drill, means to admit driving fluid alternately to opposite sides of the piston substantially at the ends of the piston and cylinder strokes, and a pawl and ratchet mechanism operatively connected to each of the 40 said two elements separately to prevent retrograde movement of each of them whilst the other makes a relative advancing movement under the action of the operating fluid.

45 19. Rock drill advancing means comprising in combination a fluid operated device having piston and cylinder elements one of which is mounted to move with a drill and has a part formed as a valve casing, a valve in said valve casing for controlling the operation of the device, means to convey driving fluid to the valve casing, and means separately to hold the said piston and cylinder elements against movement in one direction to enable them to perform alternate step by step advancing movements in the 50 opposite direction when the said device is operative.

55 20. Rock drill advancing means comprising in combination a fluid operated device having piston and cylinder elements one of which is mounted to move with a drill and has a part formed as a valve casing, a valve in said valve casing for controlling the operation of the device, means to convey driving fluid to the valve casing, and a pawl and ratchet mechanism operatively connected to each of the said piston and cylinder elements separately to prevent retrograde movement of each of them whilst the other makes a relative advancing movement under the action of the operating fluid.

60 21. Rock drill advancing means according to claim 17 comprising also means to enable the

piston and cylinder elements to perform alternate step by step retracting movements at will.

22. Rock drill advancing means according to claim 18 comprising also a further pawl and ratchet mechanism to prevent forward movement of the fluid operated device and means respectively to render the further (i. e. reverse acting) and also the forwardly acting (i. e. to prevent retrograde movement) pawl and ratchet mechanisms inoperative as desired.

10 23. Rock drill advancing means according to claim 20 comprising also a reverse acting pawl and ratchet mechanism for preventing forward movement operatively connected to that element of the fluid operated device free to move relatively to the drill, and means separately to render inoperative as desired both the forwardly acting and the reverse acting pawl and ratchet mechanism.

15 24. Rock drill advancing means comprising in combination a fluid operated device having piston and cylinder elements, one of which elements is securable to the drill, means automatically operative substantially at the ends of the piston and cylinder strokes to admit driving fluid alternately to opposite sides of the piston, and means separately to hold the said two elements against movement in one direction to enable them to perform alternate step-by-step advancing movements in the opposite direction when the said 20 device is operative.

25 25. Rock drill advancing means comprising in combination a fluid operated device having piston and cylinder elements, one of which elements is securable to the drill, means automatically operative substantially at the ends of the piston and cylinder strokes to admit driving fluid alternately to opposite sides of the piston, and a pawl and ratchet mechanism operatively connected to each of the said two elements separately to prevent 30 retrograde movement of each of them while the other makes a relative advancing movement under the action of the operating fluid.

35 26. A drilling unit comprising a pair of fluid operated motors each having a piston, one for 45 striking the steel and the other for imparting motion to the unit, a support for the unit, means actuated by the motion imparting piston to move the unit upon the support, and a mechanism co-operating with said means for controlling the 50 directional movement of the unit upon the support.

40 27. A drilling unit comprising a pair of fluid operated motors each having a piston, one for striking the steel and the other for imparting 55 motion to the unit, a support for the unit, means actuated by the motion imparting piston to move the unit upon the support, and a manually actuated mechanism controlling said means for rendering the latter inactive upon continued 60 movement of the motion imparting piston.

45 28. A rock drilling unit comprising a pair of fluid operated motors each having a piston, one for striking the work performing steel and the other for imparting motion to the unit, a support 65 for the unit, means controlling the movement of the last said piston, means responsive to the movement of the drill for actuating said piston, and the last said means being controlled at certain periods of work performed by the steel.

70 GUSTAV C. PEARSON.
IVAN S. CARPENTER.
